UNITED STATES PATENT OFFICE.

ROBERT C. MATHEWS, OF WYOMING, NEW JERSEY, ASSIGNOR, BY MESNE ASSIGNMENTS,
TO WESTERN ELECTRIC COMPANY, INCORPORATED, A CORPORATION OF NEW
YORK.

CARRIER-WAVE SIGNALING.

Application filed April 3, 1925. Serial No. 20,376.

This invention relates to carrier wave signaling and particularly to multiplex carrier telegraph receiving circuits.

An object of the invention is to provide 5 an efficient and economical multiplex carrier current telegraph system.

A related object of the invention is to obtain 10 a high degree of selectivity between various message waves employed in systems 10 of this type, with an accompanying economy in the frequency range.

From an economic standpoint, it is desirable 15 in multiplex carrier current telegraph systems to include as large a number of signaling channels as possible within a given frequency range. The closeness of spacing 20 of the frequencies assigned to the various channels depends upon the frequency range needed for the desired quality of telegraph 25 signals, and to a large extent upon the frequency separation of the bands needed to provide for selectivity. The range of the individual channel frequencies, of course, 30 cannot be reduced without impairing the quality of the telegraph signals. In accordance 35 with the present invention, however, the frequency spacing between the individual channel frequencies is materially reduced, thus rendering available additional 40 signaling channels within a given frequency range.

This is accomplished by so arranging the 45 output circuit of each receiving channel that interfering impulses from adjacent receiving channels are neutralized. A portion of the output of each receiving channel is passed through auxiliary windings on the receiving relays of the adjacent channels. The auxiliary windings are so proportioned 50 and so poled that the current therein will just annul the effects of the interfering currents in the main windings of the relays which are due to interfering impulses from the adjacent channels.

45 A particular advantage of the invention is that it may be applied to a standard audio frequency or high frequency carrier telegraph system without otherwise altering the system where cross-talk exists which it is 50 desired to reduce or eliminate.

The invention will be described in connection with the accompanying drawing which is a diagrammatic illustration of the west terminal station of a multiplex carrier

current telegraph system embodying the invention.

The usual east terminal station, which is identical to the west station shown in the drawing, is omitted for the sake of simplifying the showing. The drawing shows 60 only so much of the Morse telegraph equipment as is necessary to a complete understanding of the invention, this equipment being similar to that shown in Fig. 55 of the article by Messrs. Colpitts and Black- 65 will entitled "Carrier current telephony and telegraphy" published in the Transactions of the American Institute of Electrical Engineers, vol. 40, 1921.

The terminal circuits include a plurality 70 of transmitting channels TC_1 , TC_2 , etc., connected to a common transmitting circuit TL , and a plurality of receiving channels RC_1 , RC_2 , etc., connected to a common receiving circuit RL . The common transmitting circuit TL and the common receiving circuit RL are coupled to the multiplex transmission line ML by means of the usual hybrid coil H and balancing network N .

Carrier currents are utilized for transmission 80 over the line ML and are grouped as to their frequencies, the higher frequencies as a group being used for transmission from west to east, and the lower frequencies as a group being used for transmission from east to 85 west.

Each transmitting channel includes a source of carrier waves, a circuit for controlling the carrier waves by signal impulses, and a selective circuit. These channels are 90 identical in construction and hence reference will be made only to the apparatus of channel TC_1 .

The outgoing channel TC_1 comprises an oscillator O_1 , a sending key T_1 and a transmitting selective circuit TSC_1 . These elements are shown in detail in Figure 55 of the Colpitts and Blackwell article, supra. If desired, the selective circuit TSC_1 , however, may be either a resonant circuit such 100 as is shown in the Colpitts and Blackwell article, or may be a band filter of the type disclosed in Patent No. 1,227,113 to G. A. Campbell, issued May 22, 1917. The oscillators O_1 , O_2 , etc. are adapted to generate 105 carrier currents of the different frequencies which are assigned to the respective transmitting channels.

Normally, the output circuit of the oscillator O_1 is open at the contact of sending key T_1 . When the key T_1 is depressed, however, a carrier wave of the frequency assigned to the channel TC_1 is transmitted through selective circuit TSC_1 , common transmitting circuit TL and hybrid coil H to the multiplex transmission line ML . Carrier waves of the frequencies assigned to the other transmitting channels are similarly impressed upon the line ML .

Each receiving channel includes a receiving selective circuit, a detector and amplifier, and a receiving relay. These channels are all identical except, of course, that the constants of the selective circuits differ to the extent necessary to accommodate the different frequency carrier waves employed.

The receiving channel RC_1 , for example, comprises a receiving selective circuit RSC_1 which may be a resonant circuit or a band filter, a detector-amplifier DA_1 and a receiving relay R_1 . These elements are shown in detail in Figure 55 of the Colpitts and Blackwell article, supra. The channel RC_1 also includes a low pass filter F_1 for a purpose hereinafter to be described.

Carrier currents incoming over the line ML are transmitted through the hybrid coil H to the common receiving circuit RL where they are picked up by the respective selective circuits for transmission to the proper channels. Currents of the frequency assigned to channel RC_1 , for example, are transmitted through selective circuit RSC_1 and are amplified and detected in the detector-amplifier DA_1 . The rectified currents are transmitted through filter F_1 and caused to actuate receiving relay R_1 .

When currents of the frequency assigned to channel RC_1 are impressed upon the common receiving circuit RL , not only is a response produced in the appropriate relay R_1 , but a portion of this current is also transmitted through the selective circuit RSC_2 which is next adjacent the selective circuit RSC_1 in the frequency scale. These interfering currents, when rectified, may be sufficient to cause the false operation of the relay R_2 in the receiving channel RC_2 . The same conditions apply to the other receiving channels of the system.

The necessity for eliminating such interfering currents has heretofore imposed severe requirements on the receiving selective circuits, thus materially increasing the cost of these circuits. It has also been customary to provide a fairly wide separation between the frequency bands assigned to the respective channels, thus utilizing a considerable portion of the available frequency range which might otherwise be used for additional signaling channels. In accordance with the present invention, however, the output circuits of the respective receiving chan-

nels are so arranged that interfering impulses from adjacent channels are neutralized.

The relay R_1 in addition to its main winding 1 is provided with an auxiliary or neutralizing winding 2 connected in the output of channel RC_2 . The relay R_2 , in addition to its main winding 4 in the output circuit of channel RC_2 , is provided with two auxiliary windings in circuit, respectively, with the output circuits of the channels next adjacent thereto in the frequency scale. The auxiliary or neutralizing winding 3 of relay R_2 is connected in the output circuit of channel RC_1 , while the auxiliary winding 5 is connected in the output circuit of channel RC_3 . In this way, a measured portion of the output of each receiving channel is impressed upon an auxiliary winding of the respective receiving relays in the output circuits of the adjacent channels. The auxiliary windings 2, 3, 5, etc., are so proportioned and so poled that the currents therein will just annul the effects of the interfering currents which are impressed upon the main windings 1, 4, etc., of the receiving relays.

When several frequencies are impressed upon the common receiving circuit RL at the same time, the main current and the interfering currents in each channel may produce beats in the detectors at a frequency equal to the frequency of separation, which might tend to reduce the effectiveness of the interference neutralization. The beat frequencies, however, may be suppressed from transmission to the receiving relays by inserting a single section of a low pass filter in the output of the detectors. These filters, F_1 , F_2 , etc., may be of the type disclosed in the Campbell patent, supra.

The invention set forth herein is, of course, susceptible of various other modifications and adaptations not specifically referred to, but included within the scope of the appended claims.

What is claimed is:

1. In a multiplex carrier wave signaling system, a circuit for receiving carrier waves of different frequencies, a plurality of receiving channels associated therewith, a translating device in each of said channels controlled in accordance with waves of a particular frequency, and means associated with the translating device of each channel for preventing the actuation thereof by waves of another frequency.

2. In a multiplex carrier wave signaling system, a circuit for receiving signal-modulated carrier waves of different frequencies, a plurality of receiving channels each including a translating device associated with said circuit, means in each of said channels for transmitting mutually exclusive bands of frequencies, and means associated with the translating device of each channel for

neutralizing the effect of interfering waves of frequencies assigned to adjacent channels.

3. In a multiplex carrier wave signaling system, a circuit for receiving carrier waves of different frequencies, a plurality of receiving channels associated therewith, and a receiving relay in each of said channels having a winding connected with an adjacent channel.
- 10 4. In a multiplex carrier wave signaling system, a circuit for receiving carrier waves of different frequencies, a plurality of receiving channels associated therewith, a selective circuit in each of said channels adapted to transmit a particular band of frequencies and to greatly attenuate frequencies outside said band, a detector in each of said channels, and a receiving relay in the output of the detector in each of said channels having 15 a winding connected with an adjacent channel.

5. In a multiplex carrier wave signaling system, a circuit for receiving signal-modulated carrier waves of different frequencies, a plurality of receiving channels associated therewith, selective circuits for transmitting mutually exclusive bands of frequencies to said channels, a detector in each of said channels, a receiving relay in each of said channels having a main winding in the output of the detector therein, and auxiliary windings on said relays connected in the output of the detectors of adjacent channels, said auxiliary windings being so proportioned and so poled that the current therein will just annul the effects of interfering currents in the main windings of said relays.

6. In a multiplex carrier wave signaling system, a circuit for receiving carrier waves of different frequencies, a plurality of re-

ceiving channels each including a translating device associated with said circuit, a selective circuit in each of said channels adapted to transmit a particular band of frequencies and to greatly attenuate frequencies outside 45 said band, and means associated with each of said channels for neutralizing the effect of interfering waves of frequencies assigned to another channel.

7. In a multiplex carrier wave signaling system, a circuit for receiving carrier waves of different frequencies, a plurality of receiving channels each including a translating device associated with said circuit, a selective circuit in each of said channels 55 adapted to transmit a particular band of frequencies and to greatly attenuate frequencies outside said band, and means associated with each translating device for insuring against the operation thereof by any 60 currents from said circuit having frequencies adapted to operate adjacent translating devices.

8. In a multiplex signaling system, a transmission line for receiving currents of 65 different frequencies, a plurality of selective receiving circuits connected to said line and each having a translating device therein, each of said channels being adapted to transmit a particular band of frequencies and to 70 greatly attenuate frequencies outside said band, interconnecting means between said translating devices for insuring against the operation of each translating device by currents of the frequencies received through the 75 associated channel from the line and adapted to operate adjacent translating devices.

In witness whereof, I hereunto subscribe my name this 2 day of April A. D., 1925.

ROBERT C. MATHES.
